CLAIM

The ornamental design for a beverage container with a set of windows, as shown and described.

DESCRIPTION

FIG. 1 is a perspective view of the beverage container with a set of windows;

FIG. 2 is a front elevation view thereof;

FIG. 3 is a rear elevation view thereof;

FIG. 4 is a top elevation view thereof;

FIG. 5 is a bottom elevation view thereof; and,

FIG. 6 is a side elevation view thereof, the opposite side elevation being a mirror image thereto.

The broken lines in all figures shown represent environment and form no part of the claimed design.
